UNITED STATES PATENT OFFICE.

ALEXANDER BOGDÁNFFY, OF NEW YORK, N. Y.

HEADED STOPPER.

1,162,443.

Specification of Letters Patent. Patented Nov. 30, 1915.

Application filed November 19, 1914. Serial No. 872,966.

To all whom it may concern:

Be it known that I, ALEXANDER BOGDÁNFFY, a subject of the King of Hungary, and a resident of the city of New York, in the county of Kings and State of New York, have invented certain new and useful Improvements in Headed Stoppers, of which the following is a specification.

The present invention relates to headed 10 stoppers.

Headed stoppers or, as they are called in commerce, "wood-top corks," are usually made of two parts, towit: a tapered cork and a wooden head or flange, the latter having made integral therewith a tenon, preferably cylindrical, that is seated in a mortise or recess in the cork. In manufacturing these stoppers, first a cork is blocked from a cork strip and tapered. In the product so obtained is then formed a cylindrical mortise, into which is inserted the tenon of the wood-top or flange, said tenon being before insertion coated with a suitable adhesive, such as for instance glue. These 20 operations are performed on four separate machines, that is on the blocker, the tapering machine, the wood-top making machine and the assembling device, necessitating thus at least four operations. In practice it has been found that the two parts of the wood-top cork are apt to separate when the stopper is being withdrawn from the bottle or other container, for instance if the stopper had been inserted into the bottle or other 30 container by force.

One of the objects of the present invention is to provide a headed stopper that is made of one integral piece, more particularly it is made of artificial or composition cork, or a like substance, whereby the defects of the wood-top stoppers heretofore in use are effectively obviated and, on the other hand, the cost of producing the same is greatly reduced.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction 50 within the scope of the appended claims without departing from the spirit or sacri-

ficing any of the advantages of the invention.

One of the many possible embodiments of the invention is illustrated in the accompanying drawings, in which:—

Figure 1 is a vertical central section taken through a headed stopper made in accordance with the present invention; Fig. 2 is a bottom plan view of the same; Fig. 3 is a vertical central section taken through a mold for forming such stopper; and Fig. 4 is a front elevation of a portion of said mold.

In the drawings, the numeral 10 indicates a headed stopper, made of artificial or composition cork, or of any other suitable similar material. This stopper comprises a body 11 in the form of a frustum of a cone that is inverted, or in other words that end thereof which is of smaller diameter forms the base of the same. Upon the top of this tapering body is formed a head or flange 12, which is made integral with the said body. This flange or head, although shown in the drawings as being disk-shaped, may be of any configuration to suit the requirements.

For forming this stopper, a mold is made use of, for instance the one shown in Figs. 3 and 4 of the drawings. This mold comprises a mold body 13, in which is formed a suitable number of cylindrical bores 14. Each of these bores comprises two sections 15 and 16, the section 15 being of a larger diameter than the section 16. In each section 16 is slidably disposed a sleeve 17, provided upon its upper end, which projects into the section 15 of the bore, with a flange 18. The upper section 19 of the bore in the sleeve 17 is tapered, and below this tapered section is formed a shoulder 20, on which rests the flange 21 of an ejector 22, that is slidably disposed in the sleeve 17, and provided upon its lower end with a head 23. The ejector 22 projects beyond the lower end of the sleeve 17, the lower end of the latter having a stop 24 for a purpose hereinafter to be described. The flange 21 of the ejector 22 constitutes the bottom of the mold, its top being formed by a cover 25, to which are attached or with which may be made integral plungers or tampers 26, that fit into the sections 15 of the bores 14 in the mold body.

The lower faces 27 of the plungers or tampers may be shaped to suit the requirements. To hold the cover 25 upon the mold body, there may be provided suitable clamping devices,

for instance hooks 28, that are pivoted at 29 to the cover, and adapted to engage with studs 30 upon the mold body.

In forming the headed stoppers, a suitable 5 artificial or composition cork is provided, consisting of loose cork or other granules and of a binding material that is properly mixed with the said granules. The cover 10 of the mold is removed and the mold with the parts carried thereby placed upon a support so that the sleeves 17 and the ejectors 15 20 are in their lower positions, as shown in Fig. 3 of the drawings. The artificial cork or other suitable composition is then 25 poured into the mold, the superfluous material wiped off from the top of the mold, the plungers or tampers inserted into the sections 15 of the bores and driven home by applying pressure until the lower face of the 30 cover abuts against the mold body. The hooks 28 are then engaged with the studs 30 on the mold body. The mold is then placed 35 into an oven in which it is subjected to the action of heat for the purpose of setting, 40 coagulating or vulcanizing, as the case may be, the binding material with which the cork or other granules are mixed. The temperature employed varies, of course, according 45 to the nature of the binding material, and so does also the time during which the heating action is to be maintained. After heating, the molds are withdrawn from the oven and left to cool. After cooling, the cover 50 of the mold is removed and, first, the sleeves 17 pushed toward the upper face of the mold as far as the stops 24 on the said sleeves will permit. The ejectors are then forced upward with the result that the finished headed stoppers are removed from 55 the mold.

It will be observed that, inasmuch as the 60 composition cork or other material is packed into the mold, a homogenous body of solid cork or similar material is obtained that 65 lacks the pores, holes and other defects usually to be found in natural cork-wood. In tamping or packing the artificial cork or 70 similar material into the mold, the head 12 of the stopper being formed is subjected to considerably greater pressure than the body 75 11 thereof, and for this reason, while said body is elastic in the same degree as natural cork-wood, the head formed obtains almost the rigidity of wood. The headed stopper

formed thus possesses the qualities of the 55 wood-top stoppers heretofore in use, that is to say it comprises an elastic tapered body and a rigid head or flange. It is, however, free from the defects above described of the 60 wood-top stoppers.

What I claim is:—

1. A headed stopper comprising an elastic body in the shape of a frustum of a cone, and a head made integral therewith and formed on that end thereof which is of 65 larger diameter, said head being relatively rigid.

2. A headed stopper made of artificial cork or like material comprising a body in the shape of a frustum of a cone, and a 70 head made integral therewith and formed on that end thereof which is of larger diameter, said body being elastic and said head relatively rigid.

3. A headed stopper made of a suitable 75 composition comprising a body in the shape of a frustum of a cone, and a head made integral therewith and formed on that end thereof which is of larger diameter, said body being elastic and said head relatively 80 rigid.

4. A headed stopper comprising an elastic body in the shape of a frustum of a cone, and a disk-shaped flange made integral therewith and formed on that end thereof which is of 85 larger diameter, said flange being relatively rigid.

5. A headed stopper made of artificial cork or like material and comprising a body in the shape of a frustum of a cone, and a 90 disk-shaped flange made integral therewith and formed on that end thereof which is of larger diameter, said body being elastic and said head relatively rigid.

6. A headed stopper made of a suitable 95 composition comprising a body in the shape of a frustum of a cone, and a flange made integral therewith and formed on that end thereof which is of larger diameter, said body being elastic and said head relatively 100 rigid.

Signed at New York, in the county of New York, and State of New York, this 18th day of Nov., A. D. 1914.

ALEXANDER BOGDÁNFFY.
